RAILWAY TRAFFIC CONTROLLING APPARATUS

Application filed April 1, 1931. Serial No. 526,826.

My invention relates to railway traffic controlling apparatus, and particularly to signaling apparatus for stretches of single track over which traffic moves in both directions between passing sidings.

I will describe one form of railway traffic controlling apparatus embodying my invention, and will then point out the novel features thereof in claims.

In the accompanying drawings, Figs. 1^a and 1^b, when placed end to end with Fig. 1^a on the left, constitute a diagrammatic view illustrating one form of railway traffic controlling apparatus embodying my invention.

Referring to the drawings, the reference character A designates a stretch of railway track between points C and D, which track is divided by means of insulated joints a to form a plurality of track sections 1, 2, 3, 4, 5, 6, 7 and 8. Section 1 is connected by means of a switch E¹ with a passing siding F¹, and section 8 is likewise connected by means of a switch E⁸ with a passing siding F⁸. The control means for the switches E¹ and E⁸ form no part of my invention, and is therefore not shown in the drawings.

Each track section is provided with the usual track circuit comprising a suitable source of current, here shown as a track battery 9, connected across the rails at one end of the section, and a track relay designated by the reference character T with a distinguishing exponent, connected across the rails at the opposite end of the section.

Eastbound traffic over stretch C—D, that is, traffic moving from left to right, is governed by trackway signals H¹, H⁴, H⁶ and H⁸, located at the left hand end of sections 1, 4, 6 and 8, respectively, and westbound traffic is governed by signals J⁸, J⁵, J³ and J¹, located at the right hand end of sections 8, 5, 3 and 1, respectively. A signal H^{1a} is also located at the right hand end of siding F¹ for governing the entrance of eastbound traffic into stretch C—D from the siding F¹, and a similar signal J^{8a} is located at the right hand end of siding F⁸ for governing the entrance of westbound traffic into stretch C—D from the siding F⁸. These signals may be of any suitable form, and are here shown as light signals

each comprising three lamps G, Y and R arranged when energized to indicate "proceed", "caution", and "stop", respectively. For convenience, in describing my invention, I shall hereinafter refer to signals H¹, H^{1a}, J⁸ and J^{8a}, as head block signals; the signals H⁴, H⁶, J⁵ and J³ as intermediate signals, and the signals H⁸ and J¹ as leaving signals, but it is to be understood that these particular designations have no especial significance, and that there are no essential differences between the signals thus designated, other than the differences in their locations.

The head block signals H¹ and H^{1a} are controlled by two slow acting relays SH¹ and SH^{1a} respectively, and by a line relay SH. As here shown, the line relay SH is of the polarized type, so that it is responsive to reversals in the polarity of the current supplied thereto; and this relay is so designed that when its polar armature is moved to one position, it will remain in such one position until the relay is supplied with current of the opposite polarity from that which caused the polar armature to move to such one position. Referring particularly to signal H¹, when relay SH¹ is deenergized, a circuit is completed for lamp R of this signal, and current flows from terminal B of a suitable source of current not shown in the drawings through back contact 10—10^b of relay SH¹, wire 11, and the filament of lamp R to terminal X. Under these conditions lamp R of signal H¹ is illuminated, and the signal displays a stop indication. When relay SH¹ is energized, and the polar contacts of relay SH are swung to their left-hand or normal positions, in which positions they are illustrated in the drawings, a circuit is completed for lamp G of signal H¹, and current flows from terminal B through front contact 10—10^a of relay SH¹, wire 12, normal contact 13—13^a of relay SH, wire 15, and the filament of lamp G to terminal X. Under these conditions, lamp G is lighted, and signal H¹ displays a proceed indication.

When relay SH¹ is energized, and the polar contacts of relay SH are swung to their right hand or reverse positions, a circuit is completed for lamp Y of signal H¹, and current flows from terminal B through front contact 10—10^a of relay SH¹, wire 12, normal contact 13—13^a of relay SH, wire 15, and the filament of lamp Y to terminal X. Under these conditions, lamp Y is lighted, and signal H¹ displays a caution indication.

terminal B through front contact 10—10^a of relay SH¹, wire 12, reverse contact 13—13^b of relay SH, wire 14, and the filament of lamp Y to terminal X. Under these conditions lamp Y is lighted and signal H¹ displays a caution indication. It will be apparent, therefore, that when relay SH¹ is deenergized, signal H¹ displays a stop indication, but that, when relay SH¹ is energized, signal H¹ displays a caution or a proceed indication, according as the reverse or normal contacts of the line relay SH are closed. The circuits for signal H^{1a} are similar to those just traced for signal H¹, and will be understood from an inspection of the drawings without describing them in detail.

The head block signals J⁸ and J^{8a} are controlled by two slow acting relays SJ⁸ and SJ^{8a} and by a polarized line relay SJ in the same manner as the signals H¹ and H^{1a} are controlled by the two slow acting relays SH¹, SH^{1a} and by the polarized line relay SH. The control circuits for the signals J⁸ and J^{8a} are omitted from the drawings to simplify the disclosure.

Each of the signals H⁴, H⁶, H⁸, J⁵, J³ and J¹ is controlled by a line relay designated by the reference character S with a suffix which is the same as the reference character for the associated signal. Each of these relays is a polarized relay similar to the line relay SH previously described. Referring particularly to signal H⁴, when relay SH⁴ is deenergized, a circuit is completed for lamp R of this signal, and current flows from terminal B through back contact 28—28^b of relay SH⁴, wire 29, and the filament of lamp R to terminal X. Under these conditions, lamp R is lighted and signal H⁴ displays a stop indication. When relay SH⁴ is energized in the reverse direction so that its front contacts are closed and its polar contact 31 is swung to its right-hand or reverse position, a circuit is completed for lamp Y of signal H⁴, and current flows from terminal B through front contact 28—28^b of relay SH⁴, wire 30, reverse contact 31—31^b of relay SH⁴, wire 32, and the filament of lamp Y to terminal X. Under these conditions lamp Y is lighted, and signal H⁴ displays a caution indication. When relay SH⁴ is energized in its normal direction so that its polar contact 31 is swung to its left-hand or normal position, as illustrated in the drawings, a circuit is completed for lamp G of signal H⁴ and current flows from terminal B through front contact 28—28^a of relay SH⁴, wire 30, normal contact 31—31^a of relay SH⁴, wire 33, and the filament of lamp G to terminal X. Under these conditions, lamp G is lighted, and signal H⁴ displays a proceed indication. It will be apparent, therefore, that signal H⁴ displays a stop, caution, or proceed indication according as line relay SH⁴ is deenergized, or is energized in its reverse or its normal direction. The con-

trol circuits for each of the signals H⁶, H⁸, J⁵, J³ and J¹ are similar to those just traced for signal H⁴, and they have therefore been omitted from the drawings in order to simplify the disclosure.

The relays SH¹ and SH^{1a} are controlled by a circuit controller K¹, the track relay T¹, a circuit controller L¹, and the line relay SH. The circuit controller K¹ is operatively connected with the switch E¹ and, in the form here shown, comprises a contact 16—16^a which is closed when and only when the switch occupies its full normal position, in which position it is shown in the drawings, and a contact 16—16^b which is closed when and only when the switch occupies its full reverse position. The circuit controller L¹, as here shown, is manually operable, and comprises two contacts 17—18 and 19—20, one of which is closed when the circuit controller occupies one position, and the other of which is closed when the circuit controller occupies another position. In actual practice, the circuit controller L¹ will usually be replaced by the contacts of a relay which is controlled from a remote point, as by a lever of an interlocking machine, or by code sent out from a dispatcher's office.

Relay SH¹ is provided with a circuit which passes from terminal B through front contact 21 of relay SH, wire 22, contact 19—20 of circuit controller L¹, wire 23, front contact 24 of track relay T¹, wire 25, contact 16—16^a of circuit controller K¹, wire 26, and the winding of relay SH¹ to terminal X. When this circuit is closed, line relay SH¹ becomes energized, thereby causing signal H¹ to indicate caution or proceed according as line relay SH is then energized in its reverse or its normal direction, as pointed out hereinbefore. It will be noted, however, that this circuit cannot be closed unless track section 1 is unoccupied and switch E¹ occupies its normal position, in which position it is illustrated in the drawings.

Relay SH^{1a} is provided with a circuit which is similar to the circuit just traced for relay SH¹, and which passes from terminal B through front contact 21 of relay SH, wire 22, contact 19—20 of circuit controller L¹, wire 23, front contact 24 of track relay T¹, wire 25, contact 16—16^b of circuit controller K¹, wire 27, and the winding of relay SH^{1a} to terminal X. When this circuit is closed, relay SH^{1a} becomes energized, thereby causing signal H^{1a} to indicate caution or proceed according as line relay SH is energized in its reverse or normal direction. It will be noted, however, that this circuit cannot be closed unless track section 1 is unoccupied, and switch E¹ occupies its reverse position.

Relays SJ⁸ and SJ^{8a} are controlled by a circuit controller K⁸, the track relay T⁸, a circuit controller L⁸, and the line relay SJ.

The circuit controller K^s is similar to the circuit controller K^1 , and is operated by the switch E^s in the same manner as the circuit controller K^1 is operated by the switch E^1 . The circuit controller L^s is likewise similar to the circuit controller L^1 . The circuits for the relays SJ^s and $SJ^s a$ are similar to the circuits for the relays SH^1 and $SH^1 a$, respectively, and will be understood from an inspection of the drawings without describing them in detail.

Each of the line relays with the exception of line relays SH and SJ controls a slow releasing repeater relay designated by the reference character R with a prefix which is the same as the reference character for the associated line relay. Each repeater relay is supplied with current from the terminals B and X over a front contact of the associated line relay, and it will be apparent therefore that each repeater relay is energized or deenergized according as the associated line relay is energized or deenergized.

Associated with each of the intermediate signals H^4 , H^6 , J^5 and J^3 is a directional stick relay designated by the reference character M with the same exponent as the exponent for the reference character of the associated signal. Each repeater relay is controlled by the track relay for the section of track immediately in advance of the associated signal in the direction of traffic governed by the signal and by the repeater relay for the line relay which controls the associated signal. Referring particularly to the relay M^4 , for example, when track relay T^4 is deenergized and repeater relay $SH^4 R$ is energized, a pick-up circuit is completed for this relay which passes from terminal B through back contact 35 of track relay T^4 , wires 36 and 37, front contact 38-38^a of repeater relay $SH^4 R$, wires 39 and 40, and the winding of relay M^4 to terminal X . When this circuit is closed, stick relay M^4 becomes energized and completes a stick circuit which passes from terminal B , through back contact 35 of track relay T^4 , wires 36 and 44, front contact 42 of relay M^4 , wires 43 and 40, and the winding of relay M^4 to terminal X . Relay M^4 is further provided with another stick circuit which passes from terminal B through back contact 38-38^b of repeater relay $SH^4 R$, wires 37 and 41, front contact 42 of relay M^4 , wires 43 and 40, and the winding of relay M^4 to terminal X . It will be noted that this latter stick circuit for stick relay M^4 is closed if and only if repeater relay $SH^4 R$ is deenergized when stick relay M^4 is energized. The circuits for each of the remaining stick relays are similar to those just traced for the stick relay M^4 , and will be apparent from an inspection of the drawings without describing them in detail.

The line relay SJ^1 is controlled by a front contact 44 of track relay T^1 , and by manually

operable means forming no part of my invention and therefore not shown in the drawings. For purposes of the present disclosure, it is sufficient to say that this relay will be deenergized whenever track section 1 is occupied, and that when this section is unoccupied this relay may be deenergized, or energized in either its normal or reverse direction by the manipulation of a manually operable device or other suitable control means located at a remote point.

The line relay SH^s is controlled by a front contact 44 of track relay T^s and by manually operable means located at a remote point in the same manner as the relay SJ^1 is controlled by a front contact 44 of track relay T^1 and by manually operable means.

Line relay SJ^s is provided with a circuit which is controlled in part by repeater relay $SJ^1 R$ and which passes from terminal B through back contact 45-45^b of repeater relay $SJ^1 R$, line wire 46, winding of line relay SJ^s , wire 47, back contact 48 of stick relay M^4 , wire 49, front contact 50 of track relay T^s , line wire 51, front contact 52 of track relay T^s , front contact 53 of track relay T^1 , contact 17-18 of circuit controller L^1 , wire 54, back contact 55 of relay $SH^1 a$, wire 56, back contact 57 of relay SH^1 , wire 59, and back contact 58-58^b of repeater relay $SJ^1 R$ to terminal C . When this circuit is closed, line relay SJ^s is supplied with current of what I shall term reverse 'polarity', and under these conditions, the polar contact of this relay is swung to its right hand or reverse position so that signal J^s displays a caution indication as shown in the drawings. Relay SJ^s is also provided with a circuit which is similar to the circuit just traced for this relay, except that this circuit includes front contacts 45-45^a and 58-58^a of relay $SJ^1 R$ instead of back contacts 45-45^b and 58-58^b of relay $SJ^1 R$. When this latter circuit is closed, it will be obvious that the polarity of the current supplied to relay SJ^s is reversed, and under these conditions, the polar contact of this relay is swung to its left hand or normal position, so that signal J^s displays a proceed indication.

Line relay SH^6 is provided with a circuit which passes from terminal B through front contact 60-60^a of repeater relay $SH^6 R$, line wire 61, winding of relay SH^6 , wire 62, back contact 63 of stick relay M^6 , wire 64, front contact 65 of track relay T^6 , line wire 66, front contact 67 of track relay T^6 , front contact 68 of track relay T^s , contact 17-18 of circuit controller L^s , wire 69, back contact 70 of relay $SJ^s a$, wire 71, back contact 72 of relay SJ^s , wire 73, and front contact 74-74^a of repeater relay $SH^6 R$ to terminal C . When this circuit is closed, relay SH^6 is supplied with current of reverse polarity, and its polar contact is swung to its right hand or reverse position so that signal H^6 displays a

caution indication. Relay SH⁶ is also provided with another circuit which is similar to the circuit just traced except that this circuit includes back contacts 60—60^a and 74—74^b of relay SH⁸R instead of front contacts 60—60^a and 74—74^a of this relay. It will be apparent that when this latter circuit is closed, relay SH⁶ is supplied with current of normal polarity and, under these conditions, 10 the polar contact of relay SH⁶ is swung to its left hand or normal position so that signal H⁶ displays a proceed indication.

Line relay SH is provided with a circuit which is controlled in part by repeater relay 15 SH⁴R, and which passes from terminal B through front contact 75—75^a of repeater relay SH⁴R, wire 77, back contact 78 of repeater relay SH³R, wire 79, front contact 80 of track relay T⁴, line wire 81, front contact 82 of track relay T², front contact 83 of track relay T¹, wire 84, winding of relay SH, line wire 85, and front contact 86—86^a of repeater relay 20 SH⁴R to terminal C. When this circuit is closed, line relay SH is supplied with current of normal polarity, and its polar contacts are 25 swung to their left hand or normal positions in which they are illustrated in the drawings. Line relay SH is also provided with another circuit which passes from terminal B through back contact 75—75^b of line relay SH⁴R, line wire 85, winding of relay SH, wire 84, front contact 83 of track relay T¹, front contact 82 of track relay T², line wire 81, front contact 30 80 of track relay T³, wire 79, back contact 78 of repeater relay SJ³R, wires 77 and 87, front contact 88 of stick relay M⁴, wire 89, and back contact 86—86^b of repeater relay SH⁴R to terminal C. When this latter circuit for relay 35 SH is closed, relay SH is supplied with current of reverse polarity and its polar contacts are 40 swung to their right hand or reverse positions.

Line relay SH⁴ is provided with a circuit which is controlled in part by repeater relay 45 SH⁶R, and which passes from terminal B through front contact 90—90^a of repeater relay SH⁶R, wires 91 and 92, back contact 93 of repeater relay SJ⁵R, wire 94, front contact 95 of track relay T⁵, line wire 96, front contact 97 of track relay T⁴, wire 98, back contact 99 of stick relay M³, wire 100, winding of relay SH⁴, line wire 101, and front contact 102—102^a of repeater relay SH⁶R back to terminal C. When this circuit is closed, line 50 relay SH⁴ is supplied with current of normal polarity and its polar contacts are swung to their left hand or normal positions, in which they are illustrated in the drawings, so that signal H⁴ then displays a proceed indication. 55 Relay SH⁴ is also provided with another circuit which passes from terminal B through back contact 90—90^b of repeater relay SH⁶R, line wire 101, winding of relay SH⁴, wire 100, back contact 99 of stick relay M³, wire 98, front contact 97 of track relay T⁴, line wire 60 65

96, front contact 95 of track relay T⁵, wire 94, back contact 93 of repeater relay SJ⁵R, wires 92 and 103, front contact 104 of stick relay M⁶, wire 105 and back contact 102—102^b of repeater relay SH⁶R to terminal C. When 70 this circuit is closed, line relay SH⁴ is supplied with current of reverse polarity, and its polar contacts are swung to their right-hand or reverse positions so that signal H⁴ displays a caution indication. 75

Line relay SJ⁵ is provided with a circuit which is controlled in part by repeater relay SJ³R and which passes from terminal B through front contact 106—106^a of repeater relay SJ³R, wire 107, back contact 109 of repeater relay SH⁴R, wire 110, front contact 111 of track relay T⁴, line wire 112, front contact 113 of track relay T⁵, wire 114, back contact 115 of stick relay M⁶, wire 116, winding of relay SJ⁵, line wire 117, and front contact 118—118^a of repeater relay SJ³R to terminal C. When this circuit is closed, relay SJ⁵ is supplied with current of normal polarity, and its polar contacts are swung to their left-hand or normal positions, so that signal J⁵ displays a proceed indication. Line relay SJ⁵ is further provided with a circuit which passes from terminal B through back contact 106—106^b of repeater relay SJ³R, line wire 117, winding of line relay SJ⁵, wire 116, back contact 115 of stick relay M⁶, wire 114, front contact 113 of track relay T⁵, line wire 112, front contact 111 of track relay T⁴, wire 110, back contact 109 of repeater relay SH⁴R, wires 107 and 119, front contact 120 of stick 90 relay M³, wire 121, and back contact 118—118^b of repeater relay SJ³R to terminal C. When this latter circuit is closed, relay SJ⁵ is supplied with current of reverse polarity, and its polar contacts are swung to their right-hand or reverse positions, so that signal J⁵ displays a caution indication. 95

Line relay SJ is provided with a circuit which is controlled in part by repeater relay SJ⁵R and which passes from terminal B through front contact 122—122^a of repeater relay SJ⁵R, wire 124, back contact 125 of repeater relay SH⁶R, wire 126, front contact 127 of track relay T⁶, line wire 128, front contact 129 of track relay T⁷, front contact 130 of track relay T⁸, wire 131, winding of relay SJ, line wire 132, and front contact 133—133^a of repeater relay SJ⁵R to terminal C. When this circuit is closed, line relay SJ is supplied with current of normal polarity and its polar contacts are swung to their left-hand or normal positions. Line relay SJ is also provided with a circuit which passes from terminal B, through back contact 122—122^b of repeater relay SJ⁵R, line wire 132, winding of relay SJ, wire 131, front contact 130 of track relay T⁸, front contact 129 of track relay T⁷, line wire 128, front contact 127 of track relay T⁶, wire 126, back contact 125 of repeater relay SH⁶R, 100 105 110 115 120 125 130

wires 124 and 133, front contact 134 of stick relay M^5 , wire 135, and back contact 133-133^b of repeater relay SJ^5R to terminal C. When this circuit is closed, line relay

5 SJ is supplied with current of reverse polarity, so that its polar contacts are swung to their right-hand or reverse positions.

As shown in the drawings, stretch C-D is unoccupied so that all of the track relays T are energized. Each of the stick relays M is deenergized. Switch E^8 occupies its normal position, and contact 16-16^a of circuit controller K^8 is therefore closed and contact 16-16^b is opened. Line relay SH^8 is deenergized. Repeater relay SH^8R is therefore likewise deenergized, and signal H^8 displays a stop indication. Circuit controller L^8 occupies the position in which contact 17-18 is open, and contact 19-20 is closed. Both circuits previously traced for line relay SH^6 are therefore open at contact 17-18 of circuit controller L^8 , and relay SH^6 is therefore deenergized. Signal H^6 accordingly displays a stop indication, and repeater relay SH^6R is deenergized. Since repeater relay SH^6R and stick relay M^6 are both deenergized, both circuits previously traced for line relay SH^4 are open, and this relay is therefore deenergized. Signal H^4 therefore displays a stop indication, and repeater relay SH^4R is deenergized. The one circuit previously traced for line relay SH is interrupted at front contacts 75-75^a and 86-86^a of repeater relay SH^4R , and the other circuit for this relay is interrupted at front contact 88 of stick relay M^4 . Line relay SH is therefore deenergized. Line relay SJ^1 is also deenergized. Signal J^1 therefore displays a stop indication and repeater relay SJ^1R is deenergized. Switch E^1 occupies its normal position and contact 16-16^a of circuit controller K^1 is therefore closed while contact 16-16^b is open. Circuit controller L^1 occupies the position in which its contact 17-18 is closed and its contact 19-20 is opened. The circuit previously traced for each of the relays SH^1 and SH^1a is open at front contact 21 of line relay SH , and these relays are therefore deenergized, so that signals H^1 and H^1a both display a stop indication. The circuit previously traced for line relay SJ^3 including back contacts 58-58^b and 45-45^b of repeater relay SJ^1R is closed, and line relay SJ^3 is therefore energized in its reverse direction, so that signal J^3 displays a caution indication. The circuit previously traced for line relay SJ^5 including front contacts 106-106^a and 118-118^a of relay SJ^1R and back contact 109 of repeater relay SH^4R is also closed, so that relay SJ^5 is energized in its normal direction. Signal J^5 therefore displays a proceed indication. Line relay SJ is supplied with current of normal polarity over the circuit previously traced including front contacts 122-122^a and 133-133^a of repeater

relay SJ^5R and back contact 125 of repeater relay SH^6R , and relay SJ is therefore also energized in its normal direction. Since relay SJ is energized and since contact 19-20 of circuit controller L^8 and contact 16-16^a of circuit controller K^8 are both closed, relay SJ^8 is energized. Signal J^8 therefore displays a proceed indication. Signal J^8a , however, displays a stop indication, the circuit for relay SJ^8a being open at front contact 16-16^b of circuit controller K^8 .

In explaining the operation of the apparatus as a whole, I will first assume that with the parts in the positions just described, the train despatcher wishes to clear the signals governing eastbound traffic through the stretch C-D to permit a train approaching from the left on the main track A to enter the stretch. To do this he first operates circuit controller L^8 to open contact 19-20 of this circuit controller and to close contact 17-18. The opening of contact 19-20 deenergizes relay SJ^8 which causes signal J^8 to display a stop indication, thereby preventing a westbound train from entering stretch C-D. The operator next energizes line relay SH^8 in its normal direction, thereby causing signal H^8 to display a proceed indication. The energization of line relay SH^8 also causes repeater relay SH^8R to pick up, and this, in turn, completes the circuit previously traced for line relay SH^6 including contact 17-18 of circuit controller L^8 and front contacts 60-60^a and 74-74^a of repeater relay SH^8R , so that line relay SH^6 becomes energized in its normal direction. The energization of relay SH^6 , in turn, causes signal H^6 to display a proceed indication, and also causes repeater relay SH^6R to become energized. The train despatcher next operates circuit controller L^1 to open contact 17-18, and close the contact 19-20, of this circuit controller. The opening of contact 17-18 interrupts the circuit which was previously closed for line relay SJ^3 at this contact, and relay SJ^3 therefore becomes deenergized. This causes signal J^3 to display a stop indication, and also deenergizes repeater relay SJ^3R . The opening of front contacts 106-106^a and 118-118^a of repeater relay SJ^3R interrupts the circuit previously traced for line relay SJ^5 , and this relay also becomes deenergized. As a result, signal J^5 then displays a stop indication, and repeater relay SJ^5R becomes deenergized. The opening of front contacts 122-122^a and 133-133^a of repeater relay SJ^5R interrupts the circuit for line relay SJ and this relay likewise becomes deenergized. The closing of back contact 93 of repeater relay SJ^5R completes the circuit previously traced for line relay SH^4 including front contacts 90-90^a and 102-102^a of repeater relay SH^4R , and relay SH^4 is therefore supplied with current of normal polarity, so that this relay becomes energized in its normal direction. The en-

ergization of relay SH^4 in its normal direction causes signal H^4 to display a proceed indication and also causes repeater relay SH^4R to become energized. When front contacts 5 75-75^a and 86-86^a of repeater relay SH^4R become closed, they complete the circuit previously traced for line relay SH and line relay SH therefore becomes energized in its normal direction. The closing of front contact 10 21 of relay SH completes the circuit for relay SH^1 and this relay therefore picks up and closes its front contact 10-10^a. This, in turn, completes the circuit for the lamp G of signal H^1 , and signal H^1 therefore displays a proceed indication.

I will next assume that with signals J^8 , J^8a , J^5 , J^8 and J^1 , at stop, and signals H^1 , H^4 , H^6 and H^8 , at proceed, an eastbound train traverses the stretch C-D. When the train enters section 1, track relay T^1 becomes deenergized and opens its front contacts. The opening of front contact 24 of track relay T^1 interrupts the circuit which was previously closed for line relay SH^1 at this contact, and line relay SH^1 therefore becomes deenergized, so that signal H^1 then displays a stop indication. The opening of front contact 44 of track relay T^1 interrupts the circuit for relay SJ^1 , thus preventing the train despatcher from energizing this relay to cause signal J^1 to indicate caution or proceed as long as the train occupies section 1. The opening of front contact 83 of track relay T^1 deenergizes line relay SH . When the train enters section 2, track relay T^2 becomes deenergized and opens its front contacts. The opening of front contact 82 of this relay interrupts both circuits previously traced for line relay SH , and the opening of front contact 52 interrupts both circuits previously traced for line relay SJ^3 , thus insuring that both of these relays will remain deenergized as long as the train occupies section 2. When the train leaves section 1, track relay T^1 again becomes energized, but since line relay SH is then deenergized at front contact 82 of track relay T^2 , due to the train in section 2, the circuit for relay SH^1 remains open and signal H^1 therefore continues to indicate stop. When the train enters section 3, track relay T^2 becomes deenergized. The opening of front contact 80 of track relay T^2 maintains relay SH in its deenergized condition even though track relay T^2 now picks up due to the train having passed completely out of section 2. Similarly, the opening of front contact 50 of track relay T^3 prevents the circuit for relay SJ^3 from becoming closed as long as the train occupies section 3. It will be noted that the closing of back contact 35 of track relay T^3 does not complete the pick-up circuit for stick relay M^3 , under these conditions, because this pick-up circuit was previously opened at front contact 38-38^a of repeater relay SJ^3R when this relay became deenergized, due to the deenergi-

zation of line relay SJ^3 , and stick relay M^4 therefore remains deenergized. When the train enters section 4, track relay T^4 becomes deenergized. The opening of front contact 97 of this relay interrupts both circuits previously traced for line relay SH^4 and this latter relay therefore becomes deenergized. This causes signal H^4 to display a stop indication, and also causes repeater relay SH^4R to become deenergized. Due to the slow releasing characteristics of relay SH^4R , however, a brief interval of time elapses after relay SH^4 becomes deenergized and before front contact 38-38^a of repeater relay SH^4R opens, and since back contact 35 of track relay T^4 is then closed, the pick-up circuit for stick relay M^4 becomes completed during this interval, so that stick relay M^4 now becomes energized. As soon as stick relay M^4 closes its front contact 42, the stick circuit previously traced for this relay including back contact 35 of track relay T^4 becomes closed, and when back contact 38-38^b of repeater relay SH^4R becomes closed, the other stick circuit for this relay becomes closed. It will be apparent, therefore, that when stick relay M^4 has once become energized, this relay will remain energized as long as track relay T^4 or repeater relay SH^4R is deenergized. One function of the stick circuit for relay M^4 including back contact 35 of track relay T^4 is to insure that relay M^4 will not drop during the interval of time which elapses between the opening of front contact 38-38^a of repeater relay SH^4R and the closing of back contact 38-38^b of this relay. When front contact 88 of stick relay M^4 becomes closed, the circuit previously traced for line relay SH including this contact is completed, and line relay SH therefore becomes energized in its reverse direction. This completes the circuit for relay SH^1 , and relay SH^1 therefore picks up. Since relay SH is then energized in its reverse direction, this causes signal H^1 to display a caution indication. The opening of front contact 48 of stick relay M^4 again interrupts the circuit for line relay SJ^3 , so that signal J^3 will continue to indicate stop even though the train now passes out of section 3 and permits track relay T^3 to pick up. When the train enters section 5, and deenergizes track relay T^5 , both circuits previously traced for line relay SH^4 are opened at back contact 95 of track relay T^5 , and both circuits previously traced for line relay SJ^5 are likewise opened at front contact 113 of track relay T^5 . These relays therefore remain deenergized as long as the train occupies section 5, and signals H^4 and J^5 therefore both continue to indicate stop, under these conditions. When the train passes completely out of section 4, track relay T^4 picks up, but this has no immediate effect on the apparatus. When the train enters section 6 and deenergizes track relay T^6 , line relay SH^6 becomes deenergized and stick 130

relay M^s becomes energized. The deenergization of line relay SH^s causes signal H^s to display a stop indication, and also de-energizes repeater relay SH^sR . When track relay T^s next picks up, due to the train having passed out of section 5, the circuit previously traced for line relay SH^s including back contacts 90—90^b and 102—102^b of repeater relay SH^sR becomes closed, and relay SH^s therefore becomes energized in its reverse direction. This causes signal H^s to display a caution indication, and also causes repeater relay SH^sR to become energized. The energization of repeater relay SH^sR reverses the polarity of the current supplied to line relay SH^s , provided that a following train has not entered stretch C—D, and this latter relay then becomes energized in its normal direction. This, in turn, causes signal H^1 to display a proceed indication. The energization of repeater relay SH^sR also interrupts the stick circuit for stick relay M^s , thereby restoring stick relay M^s to its normal deenergized condition. When the train enters section 7, the subsequent deenergization of track relay T^s holds the circuit for line relays SH^s and SJ open, so that these relays cannot become energized while the train occupies this section, thus insuring that signals H^s , J^s and $J^s a$ will continue to display a stop indication under these conditions. When the train enters section 8, the circuit for line relay SH^s is interrupted at front contact 44 of track relay T^s and this relay therefore becomes de-energized, so that signal H^s now displays a stop indication. When the train passes out of section 8, track relay T^s again becomes energized and closes its front contacts. If the circuit for line relay SH^s is then open at the control point, so that repeater relay SH^sR is deenergized, line relay SH^s will become energized in its reverse direction. This will cause signal H^s to display a caution indication and also causes repeater relay SH^sR to be-
come energized. If the circuit for line relay SH^s is closed at the control point, however, when track relay T^s picks up so that repeater relay SH^sR is then energized, line relay SH^s will become energized in its reverse direction and signal H^s will display a proceed indication. The energization of repeater relay SH^sR reverses the polarity of the current supplied to line relay SH^s , thus causing this line relay to become energized in its normal direction, and hence, causing signal H^s to display a proceed indication. The energization of repeater relay SH^sR also deenergizes stick relay M^s , thereby restoring the apparatus to the condition which it occupied before the eastbound train traversed the stretch C—D.

When the signals H^1 , H^s , H^s and H^s , have been cleared to permit an eastbound move, and it is desired to restore the parts to the conditions in which they are illustrated in

the drawings, the despatcher will proceed in a manner exactly opposite to that described in connection with the clearing of the signals for an eastbound move. The operation of the apparatus under these conditions will be obvious from an inspection of the drawings without describing them in detail.

The operation of the apparatus when the parts are in the condition shown and a westbound train traverses the stretch C—D, is similar to that previously described for an eastbound train traversing the stretch, and will also be understood from an inspection of the drawings without describing it in detail.

If the parts are in the positions shown and the despatcher wishes to permit a train in the siding F^1 to enter the stretch C—D, he will of course reverse the switch E^s . This will open contact 16—16^a of circuit controller K^s and will close contact 16—16^b of this circuit controller. Relay SJ^s will then become deenergized and relay $SJ^s a$ will become energized so that signal J^s will display a stop indication and signal $J^s a$ will display a proceed indication. The operation of the apparatus in all other respects will be similar to that when a westbound train enters the stretch C—D from the main track A.

If the despatcher wishes to permit an eastbound train to enter stretch C—D from the siding F^1 , he will first reverse switch E^s and then will proceed in the manner previously described. Under these conditions relay $SH^s a$ will become energized and relay SH^s will remain deenergized so that signal $H^s a$ will indicate proceed instead of signal H^s . The operation of the remainder of the apparatus under these conditions is the same as that previously described and will be understood without further description.

It should be pointed out that with apparatus embodying my invention, it is impossible for the despatcher to clear either head block signal until the first opposing head block signal, as well as all the intervening opposing intermediate signals, have been caused to indicate stop. This arrangement clearly increases the safety of train operation in a system of this type.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of single track over which traffic moves in both directions, signals governing the entrance of traffic into said stretch, intermediate signals located at intervals along the stretch for governing traffic in both directions through the stretch, all of said signals being capable of indicating

- stop, caution, and proceed, manually operable means for separately controlling the signals governing the entrance of traffic into said stretch, in either direction, and means for rendering said manually operable means ineffective to cause such entering signals to indicate caution or proceed unless all of the opposing intermediate signals indicate stop.
2. In combination, a stretch of single track over which traffic moves in both directions, a first signal for governing traffic in one direction through said stretch, a first polarized line relay, means effective when said first line relay is deenergized for causing said first signal to indicate stop, manually operable means for causing said first signal to display a caution indication when said first line relay is energized by current of one polarity and a proceed indication when said first line relay is energized by current of the other polarity, a second signal located at some distance from said first signal for governing traffic in the opposite direction through said stretch, a second polarized line relay; means controlled by said second line relay for controlling said second signal in such manner that said second signal indicates stop, caution, or proceed according as said second line relay is deenergized or is energized by current of one polarity or the other; manually operable means for at times supplying said second line relay with current of one polarity or the other when the portion of said stretch between said signals is unoccupied, and means for at times supplying said first line relay with current of one polarity or the other when the portion of said stretch between said signals is unoccupied and said second line relay is deenergized.
3. In combination, a stretch of single track over which traffic moves in both directions, a first signal for governing traffic in one direction through said stretch, a first polarized line relay, means effective when said first line relay is deenergized for causing said first signal to indicate stop, manually operable means for causing said first signal to display a caution indication when said first line relay is energized by current of one polarity and a proceed indication when said first line relay is energized by current of the other polarity, a second signal for governing traffic in the opposite direction through said stretch, a second polarized line relay; means controlled by said second line relay for controlling said second signal in such manner that said second signal indicates stop, caution, or proceed according as said second line relay is deenergized or is energized by current of one polarity or the other, a slow-releasing repeater relay controlled by said second line relay, manually operable means for at times supplying said second line relay with current of one polarity or the other when the portion of said stretch between said signals is unoccupied, and means for at times supplying said first line relay with current of one polarity or the other when the portion of said stretch between said signals is unoccupied and said second line relay is deenergized.
4. In combination, a stretch of single track over which traffic moves in both directions, a first signal for governing traffic in one direction through said stretch, a first polarized line relay, means effective when said first line relay is deenergized for causing said first signal to indicate stop, manually operable means for causing said first signal to display a caution indication when said first line relay is energized by current of one polarity and a proceed indication when said first line relay is energized by current of the other polarity, a second signal located at some distance from said first signal for governing traffic in the opposite direction through said stretch, a second polarized line relay; means controlled by said second line relay for controlling said second signal in such manner that said second signal indicates stop, caution, or proceed according as said second line relay is deenergized or is energized by current of one polarity or the other; manually controlled means for at times supplying said second line relay with current of one polarity or the other when the portion of said stretch between said signals is unoccupied, means for supplying said first line relay with current of one polarity when the portion of track between said signals is unoccupied and said second line relay is deenergized; and means for supplying said first line relay with current of the other polarity when the portion of track between said signals is unoccupied, said second line relay is deenergized, and the portion of track immediately beyond said second signal for traffic moving in the opposite direction from that governed by said second signal is occupied.
5. In combination, a stretch of single track over which traffic moves in both directions, a first signal for governing traffic in one direction through said stretch, a first polarized line relay, means effective when said first line relay is deenergized for causing said first signal to indicate stop, manually operable means for causing said first signal to display a caution indication when said first line relay is energized by current of one polarity and a proceed indication when said first line relay is energized by current of the other polarity, a second signal located at some distance from said first signal for governing traffic in the opposite direction through said stretch, a second polarized line relay; means controlled by said second line relay for controlling said second signal in such manner that said second signal indicates stop, caution, or proceed according as said second line relay is deenergized or is energized by current of one polarity or the other; manually operable means for at times supplying said second line relay with current of one polarity or the other when the portion of said stretch between said signals is unoccupied and said second line relay is deenergized.

of said stretch between said signals is unoccupied, and said first line relay is deenergized, and means for at times supplying said first line relay with current of one polarity or the other when the portion of said stretch between said signals is unoccupied and said second line relay is deenergized.

6. In combination, a stretch of single track over which traffic moves in both directions, signals for governing traffic in one direction through said stretch and other signals for governing traffic in the opposite direction through said stretch, a plurality of line relays one associated with each signal and each arranged to control the associated signal in such manner that the associated signal indicates stop when the relay is deenergized, and means for controlling said relay in such manner that a relay associated with a signal which controls traffic in one direction cannot become energized unless the relay associated with the opposing signal which governs the entrance of traffic into the same portion of the stretch is deenergized.

7. In combination, a stretch of single track over which traffic moves in both directions, signals for governing traffic in one direction through said stretch and other signals for governing traffic in the other direction through said stretch, a plurality of line relays one associated with each signal and each arranged to control the associated signal in such manner that the associated signal indicates stop when the relay is deenergized, and means for energizing each line relay when and only when the portion of track between the associated signal and the signal next in advance governing traffic in the same direction is unoccupied and the line relay associated with the signal next in advance governing traffic in the opposite direction is deenergized.

8. In combination, a stretch of single track over which traffic moves in both directions, head block signals governing the entrance of traffic into said stretch, intermediate signals located at intervals along the stretch for governing traffic in both directions through the stretch, a plurality of line relays one associated with each of said signals and each arranged to control the associated signal in such manner that the associated signal indicates stop when the line relay is deenergized, and means for controlling said line relays in such manner that the line relay associated with each head block signal cannot become energized unless all of the line relays associated with the intermediate signals which control traffic in the opposite direction are deenergized and all of the line relays associated with the intermediate signals which control traffic in the same direction are energized.

9. In combination, a stretch of single track over which traffic moves in both directions,

signals for governing traffic in one direction through said stretch and other signals for governing traffic in the other direction through the stretch; a plurality of line relays one associated with each signal and each arranged to control the signal with which it is associated in such manner that the signal will indicate stop, caution, or proceed according as the associated relay is deenergized or is energized by current of one polarity or the other;

means for at times supplying each line relay with current of one polarity when the portion of track between the signal controlled thereby and the signal next in advance governing traffic in the same direction is unoccupied, the line relay associated with the signal next in advance governing traffic in the same direction is energized, and the line relay associated with the signal next in advance governing traffic in the opposite direction is deenergized; and means for at other times supplying each line relay with current of the opposite polarity when the portion of track between the signal controlled thereby and the signal next in advance governing traffic in the same direction is unoccupied, the line relay associated with the signal next in advance governing traffic in the same direction is energized, and the line relay associated with the signal next in advance governing traffic in the opposite direction is deenergized; and means for at other times supplying each line relay with current of the opposite polarity when the portion of track between the signal controlled thereby and the signal next in advance governing traffic in the same direction is unoccupied, the line relay associated with the signal next in advance governing traffic in the same direction is energized, and the line relay associated with the signal next in advance governing traffic in the opposite direction is deenergized; and means for at other times supplying each line relay with current of the opposite polarity when the portion of track between the signal controlled thereby and the signal next in advance governing traffic in the same direction is unoccupied, the line relay associated with the signal next in advance governing traffic in the same direction is energized, and the line relay associated with the signal next in advance governing traffic in the opposite direction is deenergized.

In testimony whereof I affix my signature.

JOHN E. McCUAULLEY.
